UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,535, dated October 18, 1881.

Application filed August 9, 1881. Term of patent 3½ years.

To all whom it may concern:

Be it known that I, HENRY HORAN, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A floral group, A, abuts against a geometrical figure, B, containing a ground-work of angular scrolls, and at one end terminating in an enlarged angular scroll, a. Below the group A is a blank field, C, and below this a geometrical figure, D, containing series of ornamental squares in its background, and ornamented 20 on top by an undulating line, b, as shown. A spray of flowers, d, traverses the figure D.

At one side of figure D is a floral group, E, above which there is a field, F, traversed by leaves. Above the field F, and partly above figure D, is a figure, G, containing a ground-work of octagons that are traversed by diametrical lines. Over this field extend floral sprays. Above the figure A is a blank field, H, traversed by leaves, and above the figure G is another blank field, I, also traversed by leaves. 30

I claim—

1. The design for carpets, consisting of the group A, substantially as shown.
2. The design for carpets, consisting of the group E, substantially as shown. 35
3. The design for carpets, consisting of the figures A B C D E F G H I a b d, substantially as shown.

HENRY HORAN.
